UNITED STATES PATENT OFFICE.

RAYMOND CALPIN, OF EVERETT, MASSACHUSETTS, ASSIGNOR TO A. S. CAMPBELL COMPANY, OF EAST BOSTON, MASSACHUSETTS, A CORPORATION OF MASSACHUSETTS.

CURTAIN-WINDOW INSTALLATION.

Application filed January 14, 1925. Serial No. 2,288.

This invention aims to provide an improved curtain window installation.

In the drawings, which illustrate a preferred embodiment of my invention:

5 Figure 1 is an inside elevation of the installation, partly broken away to show underlying parts;

10 Fig. 2 is a fragmentary view of a corner of the installation showing one of the frame members partly broken away;

Fig. 3 is an enlarged section on the line 3—3 of Fig. 1;

15 Fig. 4 is an enlarged section on the line 4—4 of Fig. 1;

Fig. 5 is an enlarged section on the line 5—5 of Fig. 1; and

20 Fig. 6 is an enlarged section on the line 6—6 of Fig. 2.

Referring to the drawings, I have shown 25 a curtain window installation particularly, though not exclusively, useful in connection with vehicle curtains. The installation, as illustrated, includes a curtain fabric 1, a light of glass 2 and a plurality of frame members 25 for positioning the glass relative to the curtain.

The purpose of this invention is to provide 30 a simple, inexpensive and durable installation which includes securing some of the frame members to the curtain "permanently" so that it is not necessary to remove them when the glass is to be replaced. To this end, I provide a one-piece frame member 3 presenting a plurality of prongs 4 and a second 35 frame member 5 presenting a plurality of prong-receiving slots 6 (Figs. 1 and 4) for cooperation with the prongs 4. These frame members 3 and 5 are secured to opposite sides of the curtain 1, as illustrated, by the prongs 40 4 substantially as shown and described in my copending application Serial No. 2,287, filed herewith. These frame parts 3 and 5 are formed substantially as shown and described in the above-mentioned application. The

45 frame member 5 presents an upstanding wall portion 7 at its inner periphery so that when the frame members 3 and 5 are secured to the curtain 1, the glass may be inserted in the space provided by the wall 7 and be supported at its periphery thereby to prevent lateral shifting of the glass. The frame member 3 projects beyond the wall 7 to support the glass at one face thereof (Figs. 3, 4 and

55 5), the curtain 1 being interposed between the glass 2 and the frame 3.

The glass 2 is cushioned at all contacting surfaces by a cushion strip 8 of uncured rubber or the like, which is stretched about the periphery of the glass and overlies a portion of each side of the glass, as illustrated. This 60 cushion strip adheres to whatever portion of the installation it contacts with and forms a seal to exclude moisture.

A third frame member 9 is provided for holding the glass 2 in place and this frame member fits between the wall 7 and beaded portion 10 of the frame member 5 and is provided with a plurality of screw-receiving holes 11. The third frame member 9 also presents an angle-shaped portion at its inner 70 periphery, which includes a flange portion 12 (Fig. 5) extending over a portion of the glass 2 to support the remaining unsupported face thereof. This frame member 9 may be secured to the rest of the installation by screws 75 13, of the self-tapping variety, which pass through the holes 11, through holes 14 in the frame 5, through the curtain 1 and thread themselves into distorted neck portions 80 formed in the frame member 3, as best illustrated in Fig. 5. Thus the third frame 9 may be easily and quickly removed from the rest of the installation by removing the screws 13, so that the glass may be changed without disturbing the rest of the frame members. 85

The frame members 5 and 9 are each formed from several pieces of metal presenting overlapping joints secured together by eyelet rivets 16, substantially as shown and described in the above-mentioned application. Thus the frames 5 and 9 may be made from the centers of the frame 3, thereby greatly reducing the cost of manufacture and using material which would otherwise be waste, in so far as curtain window frames 95 are concerned. Because of the overlapped joints and the rivets 16, as shown in Figs. 2, 3, 4 and 6, the frame 9 cannot lie against the frame 5, but touches only the rivets 16, thereby being spaced away from the frame 5 100 and also from the bent-over prongs 4, as shown in Fig. 6. However, this space is useful inasmuch as it provides means whereby tension may be exerted upon the frame member 9 to hold the glass firmly in place, when the screws are secured to the frame. The 105

screws 13 are placed at points between the joints of the frames (Fig. 1) so that tension will be distributed evenly throughout the entire frame.

5 While I have shown and described a preferred embodiment of my invention, it will be understood that changes involving omission, substitution, alteration and reversal of parts may be made without departing from 10 the scope of my invention, which is best defined in the following claims.

Claims:

1. A curtain window installation comprising, in combination, a glass, the curtain fabric, frame members secured to opposite sides of the fabric to position the glass relative to an aperture in the fabric, a third frame member for holding the glass in place and a plurality of frame-securing elements for securing 20 said third frame member to one of the other of said frame members, said securing elements being removable to permit removal of said third frame member for changing the glass while the other frame members remain secured to the curtain.

2. A curtain window installation comprising, in combination, a glass, the curtain fabric, frame members secured to opposite sides of the fabric to position the glass relative 30 to an aperture in the fabric, a third frame member having one edge overlying the glass and providing the only means holding the glass in place relative to the other frame members; and a plurality of self-tapping 35 screws passing through said third frame member through one of the other frame members, and engaging the frame member at the opposite side of the curtain, thereby detachably securing the third frame member in 40 place relative to the glass.

3. A curtain window installation comprising, in combination, a glass, the curtain fabric, a frame member located at one side of the fabric providing a support for the 45 glass, the fabric interposed between the glass and the frame member, a second frame member, means for securing said frame members to opposite sides of the fabric, said second mentioned frame member presenting 50 an inner peripheral portion surrounding the edge only of the glass to prevent lateral movement thereof, a third frame member presenting an inner flange portion overlying a portion of the glass to hold it in place 55 and a plurality of fastening elements detachably securing said third frame member to one of the other frame members to permit ready removal thereof so that the glass may be removed and replaced while the 60 other frame members remain in position.

4. A curtain window installation comprising, in combination, a glass, the curtain fabric, a frame member located at one side of the fabric providing a support for the glass, the fabric interposed between the glass and

the frame member, a second frame member secured to the opposite side of the fabric from said first mentioned frame member and presenting an inner peripheral edge portion surrounding the edge only of the glass to 70 prevent lateral movement thereof, a cushion strip surrounding the edge of the glass and overlying a portion of the adjacent face of the glass to cushion the glass relative to said frame members, a third frame member presenting an inner flange portion overlying a portion of the glass to hold it in place and a plurality of fastening elements for securing 80 said third frame member to one of the other frame members, said third frame removable to permit changing the glass while the other frame members remain secured to the fabric.

5. A curtain window installation comprising, in combination, a glass, the curtain fabric, a frame member presenting a plurality of attaching prongs, a prong-receiving and glass-positioning frame member secured to the opposite side of the fabric from the prong-presenting frame member and a cover frame, angular in cross-section, detachably secured to the other frame members for concealing the attaching prongs and for providing the only means for holding the glass in position at that side of the installation at which the cover frame lies.

6. A curtain window installation comprising, in combination, a glass, the curtain fabric and three metal frame members, one of said frame members supporting the glass at one face thereof and located at one side of the fabric, the second frame member located at the other side of the fabric and supporting the glass at its periphery only and the third frame member secured to one of the other of said frame members and supporting the glass at the opposite face from that supported by the first mentioned frame member, fastening means for permanently securing the first two mentioned frame members in place and independent fastening means for removably securing the third frame member in position to permit quick changing of the glass.

7. A curtain window installation comprising, in combination, a glass, the curtain fabric and three metal frame members, one of said frame members supporting the glass at one face thereof and located at one side of the fabric, the second frame member located at the other side of the fabric and supporting the glass at its periphery only, the third frame member secured to one of the other of said frame members and supporting the glass at the opposite face from that supported by the first mentioned frame member, and a flexible adhesive cushion strip surrounding the glass at its periphery and adjacent faces to cushion the glass relative to all of said frame members and provide moisture-proof joints.

8. A curtain window installation comprising, in combination, a glass, the curtain fabric, two glass-holding frame members secured to opposite sides of the curtain by a plurality of attaching prongs presented by one of the frame members, a beaded portion presented at the outer periphery of one of the frame members and a peripheral wall presented at the inner periphery of the same member, the wall surrounding the periphery of the glass, a cover frame presenting a base portion between the wall and the beaded portion, an angular shaped portion at the inner periphery of the cover frame presenting a flange for extension over the glass to hold it in place and a plurality of self-tapping screws for detachably securing the cover frame to the rest of the installation.

9. A curtain window installation comprising, in combination, a glass, the curtain fabric, two glass-supporting frame members secured to opposite sides of the curtain fabric, one of said frame members formed from a plurality of pieces secured together at their ends to provide joints of greater thickness than the thickness of the material from

which said pieces are formed, a third frame member resting upon said joints spaced away from said frame between the joints and extending over a portion of the glass to hold it in position relative to the remainder of the installation, and a plurality of fastening elements spaced between the joints to secure the third frame member in position and exert a tension on said third frame member thereby to hold the glass firmly in place.

10. A curtain window installation including a plurality of frame elements secured to a curtain fabric to support a glass, two of said frame elements formed from a plurality of pieces of metal secured together by eyelet rivets formed integral with said pieces, said last-mentioned frame elements spaced away from each other except at the joints, thereby to permit a plurality of self-tapping screws to exert a tension between said frame elements to hold a glass in place.

In testimony whereof, I have signed my name to this specification.

RAYMOND CALPIN.
